JAW CONSTRUCTION FOR VISES

Cedric B. Cross, Poultney, Vt., and Drayton C. Zipp, Whitehall, N. Y., assignors to Production Devices Incorporated, Whitehall, N. Y., a corporation of Connecticut

Application November 6, 1943, Serial No. 509,210

2 Claims. (Cl. 90—60)

This invention relates to vises and particularly to pressure operated vises, wherein means are provided to firmly seat the work piece in the vise.

In certain milling operations it is imperative that the work piece clamped between the vise jaws be held tightly down to a true surface, such as the bed of a vise, or on two parallels set on the vise bed. The work is then said to be bottomed. Such bottoming is customarily accomplished in a screw vise by tightening the vise and then tapping the work with a hammer until the work is properly seated or bottomed. This takes time, and on production runs the percentage of spoilage due to improper seating of work is often high. In the case of automatic vises hand bottoming cannot be easily accomplished.

A principal object of this invention is to provide vises equipped with automatic self bottoming means whereby when the vise jaws are tightened there will be a downward motion of the gripping jaw faces at the instant of gripping which will move the work piece clamped between the faces firmly down toward the vise bed and properly bottom it.

Another object of this invention is to provide self bottoming means of simple construction that may be quickly and easily applied to existing vises either of the automatic or manual type.

Still another object of the invention is to provide structure having a minimum number of working parts that may be quickly and simply assembled with resultant economies both in the speed and cost of production.

To the accomplishment of the foregoing and such other objects as may hereinafter appear, this invention consists in the novel construction and arrangement of parts hereinafter described and then sought to be defined in the appended claims, reference being had to the accompanying drawings, forming a part hereof, which shows, merely for the purposes of illustrative disclosure, preferred embodiments of the invention, it being expressly understood, however, that changes may be made in practice within the scope of the appended claims without digressing from the inventive idea.

In the accompanying drawings in which similar reference characters denote corresponding parts:

Fig. 1 is a top plan view of a vise equipped with the novel self-bottoming means of this invention, portions thereof being sectionalized to illustrate details of construction;

Fig. 2 is a side elevation of the device of Fig. 1, a portion thereof also being sectionalized to show structural details;

Fig. 3 is an end elevation viewed from the left of Fig. 2;

Fig. 4 is a sectional elevation to illustrate details of internal construction of the vise;

Fig. 5 is a top plan view of a similar vise equipped with a modified form of novel self-bottoming means of this invention, portions thereof being sectionalized to illustrate structural details; and

Fig. 6 is a sectional view taken along line 6—6 of Fig. 5, and viewed in the direction of the arrows.

Referring to the drawings, 10 denotes a base or frame for the vise having a bed, rail or keyway 11 along its top. This bed, rail or keyway 11 carries a movable jaw casting or member 12 and an adjustable fixed jaw casting or member 13.

In the embodiment shown, the movable jaw member 12 is hollow and rests on the rail or bed 11. It has downwardly depending, spaced apart flanges 15 which are slidable respectively along the oppositely-extending flanges 16 of the bed or rail 11 and serve to guide the member 12 in its movement over the rail 11. Suitable guide members or gibs, 17, are supported along the bottom edges of the respective flanges 15 by the tie down bolts 18. These members 17 extend under the rail flanges 16 so that the bolts 18 may be tightened sufficiently to guide the member 12 precisely on the rail 11. Any other suitable means may be provided to guidedly and slidably support member 12 on the bed 11.

The adjustable fixed jaw casting or member 13 has substantially similar construction. It, too, is hollow and rests on the rail or bed 11 and has spaced apart flanges 20 (only one being shown), identical with flanges 15, and gibs or clamping members 21 (only one being shown) identical with gibs or clamping members 17. The gibs 21 are supported along the bottom edges of the respective flanges 20 by the down bolts 23 identical with bolts 18. The clamping members 21 extend under the oppositely located rail flanges 16 so that bolts 23 may be tightened to clamp member 13 in a fixed position on rail 11. Any other suitable means may be provided to guidedly and slidably support the member 13 on the rail 11 and to clamp it in a fixed position thereon.

Means are provided for adjusting the position of the adjustable fixed member 13. To this end a member 25 is provided. This member has a threaded eye portion 26 extending into the space 27 of the hollow member 13, and a portion 28 secured to the frame 10 by a nut 29. An adjusting bolt 30 extends through a wall of the member

13 and threadedly engages the eye portion 26. This adjustment bolt is suitably headed at 30a and is adapted to abut an end wall of the casting 13. The position of the member 13 is thus adjustable along rail 11 by manipulation of the bolt 30 when the gibbs or clamping members 21 are loose. Any other suitable means for adjusting the position of the adjustable stationary member 13 on the rail 11 may be provided.

The movable member 12 is slideable reciprocally on the rail or bed 11. Suitable means for effecting reciprocation of said member 12 is provided. It may, for example, be that described in the co-pending application of Cedric B. Cross, Serial No. 441,877, filed May 5, 1942.

This means comprises a suitable pressure cylinder 35 of standard type adapted to be actuated preferably by air pressure. This cylinder is suitably supported in a recess 10a of the frame 10 below the rail or bed 11. The piston rod 36 of this cylinder is movable outwardly of the end of the cylinder 35 by pressure of air delivered to the latter through an inlet coupling 37 by a suitable conduit (not shown), controlled by any convenient valve (not shown).

The force transmitting means between the piston rod 36 and the movable member 12 may be of any suitable kind. In the embodiment shown, it comprises the pivoted member 42 carrying a roller 43 which is maintained in engagement with the end of plunger 36 by a suitable spring 44. A second roller 45 also carried by the pivoted member 42 engages a cam surface 46 on a lever-like pivoted member 47. The cam surface 46 is urged against roller 45 by a suitable spring 48. An arm 49 of the member 47 is connected by linkage 50 to a transverse member 51 carried by the movable member 12. Thus when the piston rod 36 moves outwardly, the movable jaw casting or member 12 is moved toward the adjustable stationary member 13 through the interaction of the parts just described in the manner indicated in detail in the aforementioned application of Cedric B. Cross. Upon release of air pressure in the cylinder 35 the piston rod 36 can move inwardly and the spring 48 operates the member 47 to retract the movable member 12 to its open position.

The particular means of effecting reciprocation of the movable member 12 with respect to the adjustable stationary member 13 may be of any suitable kind. That shown is only illustrative.

Self bottoming jaws 60 and 60a are adapted to be used with the movable member 12, and the adjustable stationary member 13. Since the jaws are identical only one need be described.

Jaw 60a consists of a frame shaped and adapted to fit slidably about the periphery of adjustable fixed member 13. The transverse leg 61a of the jaw has a jaw face Fa. The side members 62a of the jaw 60a extend parallel with the sides of said member 13. The side members 60a each have a longitudinally extending slot 63a. These slots 63a receive supporting pins 64a that are carried suitably by the member 13. These pins and slots serve to support the jaw 60a pivotally and slidably.

An inclined slot 65a is provided in each side member 62a. Pins 66a fixed in the jaw casting 13 and extending laterally therefrom engage respectively in said slots. The pins 64a and 66a in cooperation with the slots 63a and 65a serve to pivotally, slidably and guidedly support the frame 60a relative to the member 13.

Each side member 62a has a receiving recess

67a in alignment with its slot 63a. These recesses each receive a compression spring 68a. The compression springs 68a engage the respective pins 64a. These springs 68a serve to urge the jaw 60a into the position shown at Fig. 2 at which time the pins 66a lie at the bottom of their inclined slots 65a. The jaw or frame 60a then is tilted or at an inclination with the bed 11 and the inner face of its transverse leg 61a is spaced from the member 13. This is the free position of the jaw 60a. A cross piece 69a is joined to the rear ends of the side member 62a of the frame by suitable bolts 70a or the like.

The jaws 60 is fitted on the movable member 12 in the same way. The reference characters in Figures 1-4 corresponding to ones having subscripts a denote parts of identical construction. The jaw 60 is shown in Fig. 2 in the position it would occupy when the movable member 12 has been moved into clamping position toward the adjustable fixed member 13. In actual practice, before any clamping action, the jaw 60 occupies a free position on the member 12 and with respect to its pins 64 and 66 and slot 65 which is like that shown for jaw 60a. At that time the pin 66 lies at the bottom of slot 65 and the jaw frame 60 in its free position is then at an inclination with the horizontal or with bed 11. Fig. 4 shows both jaws 60 and 60a in their free positions.

30. In operation, both jaws 60 and 60a are in their free positions. The adjustable member 13 is suitably adjusted on the bed 11 and fixed thereto by clamping of gibbs 21 to accommodate a work piece of any particular type. The work piece W (Fig. 4) is then inserted between the faces F and Fa of the jaws 60 and 60a. The clamping member 12 is then moved in clamping direction toward member 13 by introduction of air into cylinder 35. This movement brings the faces F and Fa of the jaws 60, 60a into gripping contact with the work piece before member 12 has completed its stroke toward member 13. The jaws 60 and 60a are so positioned and arranged on the members 12 and 13 that the clamping stroke of member 12 is not completed until after such gripping has occurred. Then as the member 12 continues to move toward the member 13, the jaws 60 and 60a move horizontally relative to the respective jaw castings, such horizontal movement being resisted by the springs 68 and 68a so that the faces F, Fa grip the work piece firmly between them. At the same time and during such movement, the pins 66, 66a engaging in the inclined slots 65, 65a, cause the respective jaws 60, 60a to rotate or swing downwardly about pins 64, 64a as pivots. The resisting action of springs 68 and 68a has, however, caused the faces F, Fa to grip the work piece W firmly before the downward swinging action occurs. Thus a downward force will be exerted by the faces F, Fa of the jaws 60, 60a on the work piece. Stiffer springs 68, 68a, will result in a larger downward force on the work piece as this downward force is due entirely to the friction between the work piece and the jaw faces F, Fa as they move downwardly.

70. The downward motion of the jaw faces F, Fa continues until the resisting force of the springs 68, 68a, plus the friction between the jaw faces F, Fa and the work piece, and between the pins 66, 66a and inclined slots 65, 65a, equals substantially the available force exerted by the clamping member 12, or until the jaws 60, 60a have swung to the position of jaw 60 in Fig. 2 at which time they are parallel with, and in contact with, the bed 11 of the vise.

In either event, the movement of the jaws 60, 60a as just described and the downward forces exerted on the work piece, will move the latter down firmly against the vise bed 11. This will occur even if the member 12 should have a tendency to lift in relation to the vise bed 11 because of a loose fit such as might occur when the parts become worn. The jaws thus constitute automatic self-bottoming means for work pieces in a vise.

A modified form of such bottoming jaws to be applied to the movable and adjustable members is shown in Figs. 5 and 6. In these figures the vise 10' is substantially identical with that of Figs. 1 to 4 inclusive. This vise has a movable member 12' substantially identical with member 12 of Figs. 1 to 4 inclusive and an adjustable fixed member 13' substantially identical with adjustable fixed or stationary member 13. These members 12' and 13' are supported from the base 10' in the same manner as members 12 and 13 and are operated in the same way. The members 12' and 13' are shown in a reversed position from that of members 12 and 13 of Figs. 1 to 4, the vise of Figs. 5 and 6 having been rotated through 180° relative to the vise of Figs. 1-4.

Each of the members 12', 13' is provided with vertically extending bores 80 which receive springs 81 for a purpose to be presently described. Each of the members 12' and 13' has a recess or groove 83 provided with a sloping wall 84. Each groove 83 extends transversely substantially the width of the respective members 12' or 13'. The walls 84 of the respective grooves slope in opposite directions.

Self-bottoming jaws 86, 86a are adapted to be used with the movable member 12' and adjustable fixed member 13'. Since these jaws are identical only one need be described.

Jaw 86 consists of a frame shaped and ad-measured to fit slidably about the periphery of the movable member 12'. The transverse leg 87 of this jaw has a jaw face F'. This leg 87 has a transverse groove 88 extending parallel with the groove 83 and a wall 89 of this groove is parallel with the sloping wall 84.

The side members 90 of the jaw 86 each has a longitudinally extending slot 91. These slots receive supporting pins 92 that are carried suitably and fixedly by the member 12'. Each member 90 has a flange 93 that carries an adjustable abutment member or set screw 94. The latter are adapted to engage the corresponding supporting pins 92 and thereby to limit horizontal movement of the member 90 in one direction.

A suitable roller 95 is positioned in the recesses 83 and 88. A suitable cover plate 96 overlies the jaw 86 being attached to the latter in any suitable way. The springs 81 carried in the member 12' abut the cover plate 96. A suitable cross piece 97 is joined to the rear ends of the side members 90 by suitable bolts 98 or the like.

The Jaw 86a is fitted on the stationary member 13' in the same way. The reference characters in Figs. 5 and 6 corresponding to ones having subscript a denote parts of identical construction.

The jaw 86 is shown in Fig. 6 in the position it would normally occupy, while the jaw 86a is shown in a position it would occupy when bottoming of the work piece has been effected. In actual practice both jaws 86 and 86a are initially in free positions resembling that of jaw 86. At this time the jaws are tilted with respect to the bed 11' and the jaw faces F' and F'a are held

up and slightly toward each other by the action of the springs 81 which press against the covers 96, 96a. The forward motion of the jaw faces F' and F'a, induced by springs 81, toward each other, is limited by the set screws 94 which engage the pins 92. The limited forward motion also limits the upward motion of the jaw faces F' and F'a because of the interaction between the respective rollers 95, 95a and the respective sloping walls 84, 89 and 84, 89a.

When a work piece is clamped between the jaw faces F' and F'a, these jaw faces are forced back in relation to the members 12' and 13' and this backward motion forces the jaw faces F' and F'a to rotate downwardly because of the guiding or camming action between the said sloping walls 84, 89 and 84, 89a and respective rollers 95 and 95a.

The downward rotary motion of the jaw faces F' and F'a continues until the bottom edges of the jaw faces F' and F'a engage the vise bed 11', i. e., the position of jaw 86a in Fig. 6, or until frictional forces between the work piece and the jaw faces F' and F'a equal the downward moment on the inclined surfaces 89, 89a. Such downward motion of the jaw faces forces the clamped work piece firmly down toward the vise head 11, i. e., firmly bottoms the said work piece.

An advantage of the modified form is that the jaws 86, 86a instead of sliding on pins like pins 65, 65a, roll on the rollers 95, 95a. Since there is less friction, the surfaces 84, 89 and 89a can be steeper than the inclined slots 65, 65a. As a result there is less lateral motion of the jaws 86, 86a with respect to the members 12', 13' than there is of the jaws 60, 60a with respect to the members 12, 13. The smaller lateral motion is an advantage.

As with the first modification, the strength of the springs 81 will determine the extent of downward force available at jaw faces F' and F'a for bottoming action on the work piece.

Another advantage of the modified form is that it is somewhat simpler to construct than the first named form.

It must be understood that the principles and jaw structure disclosed are adaptable either for pressure operated vises or manually operated vises. Likewise no limitation is placed on the size or shape of the members to which the jaws are applied. Furthermore, while specific arrangements have been described, it is to be understood that variations in structural detail within the scope of the appended claims is contemplated. There is no intention of limitation to the exact details shown and described.

What is claimed is:

1. A vise comprising a bed, a stationary member on said bed, a second member movable toward said stationary member for effecting clamping of a work piece in said vise, a jaw carried by said stationary member, pin and slot means for supporting said jaw pivotally and slidably on said stationary member, pin and inclined slot means for guiding the pivoted and slidable motion of said jaw, a second jaw carried by said movable member, pin and slot means for supporting said second jaw pivotally and slidably on said movable member, pin and inclined slot means for guiding the pivoted and slidable motion of said second jaw, spring means resisting relative motion of each jaw with respect to the member on which it is supported and tending with the respective pin and inclined slot means to maintain the jaws in lifted position relative to

said bed, said jaws being positioned on the respective members to grip said work piece prior to completion of clamping movement of said movable member, and both said pin and inclined slot means, serving when said work piece is gripped between said jaws to urge said jaws toward said bed against the resisting action of said spring means, the latter then causing frictional engagement between said jaws and said work piece whereby said work piece is then moved with said jaws toward said bed and bottomed.

2. A vise comprising a bed, a pair of members at least one of which is movable toward the other for effecting clamping of a work piece in said vise, a jaw carried by one of said members, pin and slot means for supporting said jaw pivotally and slidably on said one of said members, roller means and inclined surfaces in conjunction with said jaw and said one of said members for guiding the pivoted and slidable motion of said jaw, a second jaw carried by the second of said members, pin and slot means for supporting said sec-

ond jaw pivotally and slidably on the second of said members, roller means and inclined surfaces in conjunction with said second jaw and said second member, spring means resisting relative movement of each jaw with respect to the member on which it is supported and tending with the respective roller means and inclined surfaces to maintain the jaws in tilted position relative to said bed, said jaws being positioned on their supporting members to grip said work piece prior to completion of clamping movement of the movable of said members and both said roller means and inclined surfaces serving when said work piece is gripped between the jaws to urge the latter toward said bed against the resisting action of the spring means, the latter then causing frictional engagement between the jaws and work piece, whereby the said work piece is moved with said jaws toward said bed and bottomed.
